CLAIM

The ornamental design for a garage light assembly as shown and described.

DESCRIPTION

FIG. 1 is a top, front, right side perspective view of a lamp portion of the garage light assembly, shown separately for clarity of illustration.

FIG. 2 is a bottom, rear, left side perspective view thereof; FIG. 3 is a front view thereof of the FIG. 1;

FIG. 4 is a back view thereof of the FIG. 1;

FIG. 5 is a left view thereof of the FIG. 1;

FIG. 6 is a right view thereof of the FIG. 1;

FIG. 7 is a top view thereof of the FIG. 1;

FIG. 8 is a bottom view thereof of the FIG. 1;

FIG. 9 is a bottom, front, right side perspective view of a Y-shaped connector portion of the garage light assembly, shown separately for clarity of illustration.

FIG. 10 is a top, rear, left side perspective view thereof;

FIG. 11 is a front view thereof of the FIG. 9;

FIG. 12 is a back view thereof of the FIG. 9;

FIG. 13 is a left view thereof of the FIG. 9;

FIG. 14 is a right view thereof of the FIG. 9;

FIG. 15 is a top view thereof of the FIG. 9;

FIG. 16 is a bottom view thereof of the FIG. 9;

FIG. 17 is a bottom, front, left side perspective view of a V-shaped connector portion of the garage light assembly, shown separately for clarity of illustration.

FIG. 18 is a top, rear, right side perspective view thereof;

FIG. 19 is a front view thereof of the FIG. 17;

FIG. 20 is a back view thereof of the FIG. 17;

FIG. 21 is a left view thereof of the FIG. 17;

FIG. 22 is a right view thereof of the FIG. 17;

FIG. 23 is a top view thereof of the FIG. 17;

FIG. 24 is a bottom view thereof of the FIG. 17;

FIG. 25 shows a top, perspective view of the design consisting of an assembled combination of the first, second and third component parts of the garage light assembly.

(Continued)

27

FIG. 26 shows a bottom, perspective view of the design consisting of an assembled combination of the first, second and third component parts of the garage light assembly. FIG. 27 is a partial enlargement of FIG. 25; and, FIG. 28 is a partial enlargement of FIG. 26.

The broken lines in the drawings depict portions of the garage light assembly that form no part of the claimed design. The additional short-dash-long-dash broken lines enclosing portions of the design in FIGS. 25-28 are enlargement borders that form no part of the claimed design.

1 Claim, 28 Drawing Sheets
